UNITED STATES PATENT OFFICE.

HOWARD A. BURKHART, OF PETERSBURG, INDIANA.

PHOTOGRAPHIC DEVELOPING-MACHINE.

1,265,169.

Specification of Letters Patent.

Patented May 7, 1918.

Application filed November 12, 1917. Serial No. 201,560.

To all whom it may concern:

Be it known that I, HOWARD A. BURKHART, a citizen of the United States, residing at Petersburg, in the county of Pike and State 5 of Indiana, have invented certain new and useful Improvements in Photographic Developing-Machines, of which the following is a specification.

This invention is a developing machine 10 and is more particularly adapted for the tank developing of films in strips, wherein the film is immersed in the developing solution or agent, while standing sidewise in a vertical plane in an extended condition.

15 In the usual method of developing films in tanks, the film is rolled in a light proof apron, which is then placed in a solution cup. To provide for the developing solution coming into contact with the film, the 20 apron has a serrated rubber strip secured to each longitudinal edge. This rubber strip is of sufficient thickness to space the convolutions of the apron, and the serrations permit the developing agent to pass to the 25 film wound within the apron.

To prepare the film for developing in the tank, the protective paper is first unrolled a sufficient distance so that the end of the film may be attached to the paper.

30 The film is then placed in the holder and the end of the paper is then secured to the shaft of a metal spool. As the holder and spool are preferably mounted in a light tight box, the lid is put on and the film is wound in 35 the metal spool between the apron convolutions.

After the film has been subjected to the action of the developer for a predetermined length of time at a specified temperature, 40 the metal spool carrying the apron and film is removed from the solution cup. The apron and film are washed, and the apron is unrolled to permit the removal of the film strip.

45 At the same time it is necessary to separate the protective or backing paper from the film and apron. As the tank is often used by the amateur, who has little room in which to work, this causes a litter that must 50 be cleaned up after development. The apron has to be washed and dried.

To overcome the disadvantages of tank de-

velopment employing an apron, the invention has for one of its objects to provide a tank without an apron and to provide for 55 separating the paper backing from the film strip simultaneously with the unwinding of the film paper from the film spool.

Another object is to provide a tank where- 60 in the film strip is positioned edgewise vertically in the developing solution or agent and supported in an extended flat condition.

A further object is to provide a tank, without an apron wherein two film strips 65 may be simultaneously developed in an ex- tended position, and passed vertically edge- wise through the developing solution when the film spools are unwound.

A still further object is to provide a tank including film spool holders with a verti- 70 cally positioned division wall therein hav- ing rollers at each end over which passes an endless chain that carries clips adapted to be attached to one end of the paper and film strip for extending the film. 75

One purpose is to provide a tank with suitable ports for ingress and egress of liquids which ports are so constructed that the danger of light fogging the photo- 80 graphic film strip is eliminated when filling and emptying the tank of liquid.

The invention broadly stated comprises an approximately rectangular receptacle having a rounded end, ingress and egress ports for a liquid, a division wall supported 85 centrally and longitudinally of the receptacle, said division wall being provided with rollers at each end, each of said rollers being provided with a sprocket intermediate its ends, said sprockets being of lesser di- 90 ameter than the rollers, a chain to coöperate with the sprockets, a carrier connected to said chain and provided with film clips that are supported above the bottom of the receptacle by a roller carried at the end of 95 a vertical rod, said clips and rod being spaced from each other and from the chain, a plurality of spool holding elements, resili- ent means to coöperate with the spools when upon said spool holders for preventing a 100 too rapid unwinding of the films and paper backing from the film spool, a plurality of spaced guides adjacent the rounded end of the receptacle and adapted to engage with

the paper and film when being carried around through said receptacle, said chain being adapted to lie in longitudinal grooves formed upon each flat surface of the division wall, and means for driving the chain and moving the film and paper through the developing agent.

One practical form of construction and assembly will be described and illustrated 10 in the accompanying drawings, in which:—

Fig. 1 is a top plan view with the cover removed and a portion of the division wall and one spool broken away,

Fig. 2 is a vertical longitudinal sectional view on the line 2—2 of Fig. 1,

Fig. 3 is a sectional view on the line 3—3 of Fig. 2,

Fig. 4 is a sectional view on the line 4—4 of Fig. 2,

Fig. 5 is a detail view showing the spool holding devices and the resilient means for engaging with the spool and the filling pipe connected to the port,

Fig. 6 is a perspective view of the resilient means employed for preventing a too rapid unwinding of the film spools, and

Fig. 7 is a detailed perspective view showing the film clips in their spaced relation and the means of supporting them in a vertical direction with portions of the arms connecting the carrier to the chain.

In the preferred embodiment about to be described the developing machine comprises a tank that may be generally indicated A. The tank or receptacle A is approximately rectangular in form and has one of its ends rounded as indicated at B. The tank may be formed of any suitable material and is provided on its upper side with a suitable opening. The edges of the receptacle A forming the edges of this opening are provided with rabbets 10 which form shoulders that are adapted to engage with suitable shouldered portions formed on the cover 11. The opening preferably extends over the greater portion of the top and adjacent the left or operating end is provided with a permanent cover indicated at 12.

The cover 11 which is made removable for the purpose of allowing access to the interior of the receptacle may be secured in proper position relative to the receptacle A so as to provide a liquid tight joint by any usual or customary means. One way of securing the cover in position is by means of the spring clips 13 shown in Figs. 3 and 4. The cover 11 is provided adjacent its rounded end with a plurality of depending and spaced rollers 14. Two of these rollers are shown in Fig. 2 while in Fig. 1 three complementary rollers 15 are shown.

The rollers 15 are secured to the bottom wall of the receptacle and are preferably in alinement with the rollers 14. These 65 rollers serve to guide the paper backing and

film strip 16 around the curved end so as to provide against undue bending of the film. These rollers 14 and 15 have their ends spaced apart, or in other words they do not contact at their ends. This is done 70 to provide space for permitting the carrier to pass between the ends of the rollers when drawing the films to their extended position.

Disposed within the receptacle A there 75 is a division wall 17 that extends substantially throughout the greater portion of the length of the receptacle. This division wall may be constructed and attached to the bottom wall 18 of the receptacle by means of 80 the pedestals or supports 19, 20, and 21. The division wall 17 is thus supported above the bottom wall 18, and the cover 11 is spaced above it.

At the ends of the division wall there are 85 formed semi-circular grooves 22 and 22^a respectively that extend vertically as indicated in Fig. 1. The ends of the groove 22 are partly closed by flanges 23 and 24 that are adapted to provide bearings for the shaft 25. 90 To permit the shaft 25 to be properly positioned within the flanges 23 and 24, the flanges are provided with open ended slots 27 and 28. Disposed within the semi-circular groove 22 there is a roller 29, and 95 its roller is mounted on the shaft 25. The groove 22^a has its ends closed by the flanges 23^a and 24^a. The flanges have open ended slots 27^a and 28^a that are adapted to receive the shaft 26. This shaft carries a 100 roller 30 that is rotatable in the groove 22^a. These rollers are of a trifle less diameter than the semi-circular groove.

Intermediate the ends of the roller 29 it is provided with a suitable groove. This 105 groove is provided with teeth that form a sprocket wheel 31. The roller 30 is provided with a sprocket 32 intermediate its ends, and this sprocket is in alinement with the sprocket 31. To coöperate with the 110 sprockets 31 and 32 a chain 33 is provided. To enable the chain 33 to pass between the sprockets and lie below the surface of the division wall 17, the division wall is provided on opposite sides 115 with the grooves 34 and 35. The shaft 26 has its lower bearing in the pedestal or support 19 and its upper end is preferably squared as indicated at 36. To coöperate with this squared end there is provided a 120 socket 37 having a flange 38 to which is connected a suitable handle 39.

The socket 37 is provided with a square hole to engage with the squared end 36 of the shaft 26. The flange 38 is adapted to 125 fit within a hole or port 40 that is formed in a suitable upstanding portion 41 formed in the top or permanent cover 12. This projecting portion or annulus is provided exteriorly with screw threads and to co- 130

operate with these threads there is a cap 42. The cap 42 is provided with a central aperture through which passes the upstanding portion of the handle 39.

5 The construction just outlined will provide a light tight port and the handle 39 will serve to drive the shaft 26 causing the chain 33 to move around the rollers 29 and 30. The chain 33 in moving around the 10 rollers will also rotate them. The cap 42 will permit the removal of the handle 39, the flange 38, and the socket 37 from engagement with the end of the shaft 26 and also from the cover 12.

15 To provide for attaching the end of the paper backing or protective strip for the film strip a carrier is provided which is shown more particularly in Fig. 7. There are provided two film or backing clips 43 and 44. These may be of any usual or customary type of construction and are preferably carried in a spaced relation by means of the arm 45. Extending from the arm 45 is a vertical member 46 that is provided at 25 its lower end with a roller 47.

The vertical member 46 will thus serve as a support for the arm 45 carrying the film clips. The roller 47 is adapted to engage with the upper surface of the bottom 30 wall 18. To support the clips in their proper vertical position and to attach the supporting member 46 to the chain the arms 48 and 49 are provided. These arms 48 and 49 extend angularly from the member 46 35 to which they are fixedly secured. Their other ends are attached to the chain 33 in any suitable or convenient manner. The arms 48 and 49 by their angularity will serve to position the arm 45 properly so as 40 to move the two clips 43 and 44 simultaneously. And at the same time the support member 46 will maintain the clips in their vertical position.

The cover 12 carries adjacent one side two 45 suitably mounted film spool holders. As shown these consist of the thumb nuts 50 and 51 attached to the upper end of the movable rods 52 and 53. The rod 52 is provided with a collar 54 and on the rod between 50 the collar 54 and the cover 12 there is disposed a spring 55. The rod 53 is provided with a similar construction having the collar 56 and the spring 57. The lower ends of the rods 52 and 53 are adapted to enter and 55 engage with the holes formed in the ends of the film spools. The springs 55 and 57 serve to maintain the rods 52 and 53 in their engagement with their respective holes.

To support the film in proper position 60 from the bottom wall 18 of the receptacle the standards 58 and 59 are employed. These standards may be secured to this bottom wall in a spaced relation in any suitable manner so that they will extend vertically. 65 Their upper ends may be provided in any

workmanlike manner with suitable devices or means for engaging with the holes formed in the lower ends of the film spools. The means employed should be such that the film spools indicated at 60 and 61 are maintained in their proper position so that the holders carried by the cover 12 may hold them in proper position.

5 The construction just outlined will provide a light tight port and the handle 39 will serve to drive the shaft 26 causing the chain 33 to move around the rollers 29 and 30. The chain 33 in moving around the rollers will also rotate them. The cap 42 will permit the removal of the handle 39, the flange 38, and the socket 37 from engagement with the end of the shaft 26 and also from the cover 12.

15 To provide for attaching the end of the paper backing or protective strip for the film strip a carrier is provided which is shown more particularly in Fig. 7. There are provided two film or backing clips 43 and 44. These may be of any usual or customary type of construction and are preferably carried in a spaced relation by means of the arm 45. Extending from the arm 45 is a vertical member 46 that is provided at 25 its lower end with a roller 47.

The vertical member 46 will thus serve as a support for the arm 45 carrying the film clips. The roller 47 is adapted to engage with the upper surface of the bottom 30 wall 18. To support the clips in their proper vertical position and to attach the supporting member 46 to the chain the arms 48 and 49 are provided. These arms 48 and 49 extend angularly from the member 46 35 to which they are fixedly secured. Their other ends are attached to the chain 33 in any suitable or convenient manner. The arms 48 and 49 by their angularity will serve to position the arm 45 properly so as 40 to move the two clips 43 and 44 simultaneously. And at the same time the support member 46 will maintain the clips in their vertical position.

The cover 12 carries adjacent one side two 45 suitably mounted film spool holders. As shown these consist of the thumb nuts 50 and 51 attached to the upper end of the movable rods 52 and 53. The rod 52 is provided with a collar 54 and on the rod between 50 the collar 54 and the cover 12 there is disposed a spring 55. The rod 53 is provided with a similar construction having the collar 56 and the spring 57. The lower ends of the rods 52 and 53 are adapted to enter and 55 engage with the holes formed in the ends of the film spools. The springs 55 and 57 serve to maintain the rods 52 and 53 in their engagement with their respective holes.

To support the film in proper position 60 from the bottom wall 18 of the receptacle the standards 58 and 59 are employed. These standards may be secured to this bottom wall in a spaced relation in any suitable manner so that they will extend vertically. 65 Their upper ends may be provided in any

workmanlike manner with suitable devices or means for engaging with the holes formed in the lower ends of the film spools. The means employed should be such that the film spools indicated at 60 and 61 are maintained in their proper position so that the holders carried by the cover 12 may hold them in proper position.

5 To prevent an undue winding or to retard the rotation of the film spools some means should be employed. One means is illustrated in Fig. 6 which shows a single sheet of metal having its sides 62 and 63 bent at right angles to the base or body portion 64. These sides 62 and 63 are then curved as 80 indicated at 65 and 66. These curved portions should be substantially of the same curvature as the film spools 60 and 61. To support this resilient restraining means the angle arms 67 and 68 are provided. The 85 arm 67 is provided with a flat section 69 having the holes 70 therein, and the arm 68 is provided with a flat section 71 having the hole 72. The holes 70 and 72 may have passed therethrough any suitable or usual 90 fastening means. These flat ends 69 and 71 are preferably secured to the side wall 73 of the receptacle as shown more particularly in Fig. 4.

The cover 12 is provided with a port 95 from which extends a pipe 74 that extends downward and is bent toward the film supports 58 and 59 and terminates in a Y having the two outlets 75 and 76. The upper end of the pipe 74 may be secured in a 100 sleeve or bushing 77 which is further secured in the port formed in the cover 12. The sleeve or bushing 77 may be adapted to receive any usual or suitable closing devices such as a stopper (not shown).

The lower wall 18 may be provided adjacent the square end with a port to which is connected a pipe 78. This pipe 78 may be employed as means for emptying the solution from the tank when so desired. The 110 pipe 78 may be closed by any usual or convenient means, such as a stopper (not shown).

When it is desired to develop roll films such as are commonly used in hand cameras, 115 the film spool is removed from the camera and engaged with the spool holders. The spools are placed upon the standards 58 and 59 and in order to hold them in proper position the shafts 52 and 53 are pulled up by 120 means of their thumb nuts 50 and 51. When the spools are in proper position the shafts 52 and 53 will engage with the upper holes of the film spools. The protective paper from spool 61 is unwound and its end inserted in the clip 43.

The end of the paper for the spool 60 is placed in the clip 44. The clips 43 and 44 are assumed to be adjacent the film spools 60 and 61. The cover 11 is replaced and 125

one end is adapted to engage with the tongue 79 and when its edges engage with the rabbets 10 the clips 13 are moved to hold the cover in a liquid tight engagement with 5 the receptacle or tank A.

The handle 39 is moved to rotate the shaft 26 which causes the roller 30 to rotate and the sprocket 32 engaging with the chain 33 will cause the roller 31 to rotate. As the 10 chain moves, the clip carrying device will be moved and the wheel 47 and the supporting standard 46 will serve to maintain the clips 43 and 44 in a vertical position. The 15 clips will then pull the paper and film along- side the division wall 17 around the roller 31 and the guide rollers 14 and 15 thence down the opposite side of the division wall 17. The carrier will then come to rest adjacent the starting end of the film but upon 20 the opposite side of the division wall 17.

As the two films 16 and 16^a are drawn to their extended position the film carrier will cause the films that are being unwound from the spool 60 to be engaged with the guide 25 rollers 14 and 15. The space between the ends of the guide rollers 14 and 15 will permit the arm 45 to pass therebetween. These 30 rollers 14 and 15 are preferably loosely mounted so that little friction is encountered as the film passes in contact with them.

The film being unwound from the spool 61 lies adjacent the sides of the division wall 17 and in contact with the roller 29. Thus it will be seen the necessity of having the roller 35 29 of sufficient size so that the film will not be unduly bent in passing around.

As shown in the several views, the two films are spaced a sufficient distance apart so that the developer may reach the full 40 surface of the sensitized film so that the developing action may take place simultaneously over the entire length of the film strip. It will be seen that the entire film surface is exposed to the action of the developer which 45 has perfect freedom of access to all portions.

Again it will be noticed that the film is drawn edgewise so that the film stands vertically and is spaced from the bottom wall 18 of the tank. The developer may be introduced through the sleeve or bushing 77 and by means of the branches or outlets 75 and 76 of the pipe 74 the developer will be directed more or less generally along the line of travel of the film. The action of the 55 developing agent which is a liquid will tend to cause a separation of the paper from the film strip so that the two may be readily parted and withdrawn without making the litter that usually comes from developing 60 with the apron type of tank.

If desired the developer may be placed within the tank as soon as the film clips are attached to their respective terminals of the film spools and then the handle 39 operated 65 to draw the carrier along one side of the

division wall 17 and down the other. If desired the film may be extended prior to the introduction of the developing agent.

The one particular feature of the device is that the film is drawn endwise through the 70 tank and is properly supported at different points so that the developing agent does not have to flow through any small openings to reach the film. Thus both of the films are placed in a clear and unrestricted position 75 so that the developing agent may have free access to the sensitized surface.

In the construction shown the roller 30 may be dispensed with and the sprocket 32 simply secured upon the shaft 26 so as to co- 80 operate with the chain 33 and the grooves 34 and 35.

What I claim is:—

1. A photographic developing machine comprising a tank including a cover, a film 85 spool holder mounted adjacent one end of the tank, and means in the tank for drawing a film vertically endwise in a horizontal plane through the tank.

2. A photographic developing machine, 90 which comprises a tank including a cover, a film spool holder mounted adjacent one end of the tank, a division wall extending longitudinally of the tank, and movable means in the tank adapted to engage with one end 95 of the film for extending and positioning the film upon opposite sides of the wall.

3. A photographic developing machine, which comprises a tank including a removable cover, means for removably retaining 100 the cover on the tank, filling and emptying ports, a division wall secured to the bottom wall of the tank and extending longitudinally thereof, said wall also being spaced from the side walls and cover of the tank, 105 a film carrier operable around the wall for unrolling and extending the film, means carried by the bottom wall and cover adjacent one end serving to guide and space the film intermediate its ends, and means for moving 110 said carrier to extend the film vertically endwise.

4. A photographic developing machine, which comprises a tank having a cover, means for detachably holding said cover on 115 the tank, a film spool holder mounted in the tank and adapted to hold the spool vertically, a division wall secured in the tank and spaced from the wall thereof and the cover, a shaft rotatably and removably mounted at one end of the wall, said shaft being provided with a roller having a sprocket intermediate its ends, a shaft having 120 a sprocket thereon, said shaft being rotatably and removably secured at the opposite end of the wall, a chain to coöperate with the sprockets, said sprockets being substantially in alinement horizontally for maintaining the chain between the upper and lower sides of the division wall, a film car- 125 130

rier which includes a pair of spaced clips, a plurality of arms angularly extending from adjacent the clips and having their other ends connected to the chain, and means for 5 moving the chain and carrier for unrolling and extending the film upon each side of the division wall.

5. A photographic developing machine, which comprises a tank having a cover, inlet 10 and outlet ports for the tank, a pipe connected to one of the ports, said pipe being curved and terminating in a Y, a plurality of film spool holders mounted in the tank each having means for releasably holding 15 the spools, a longitudinally grooved division wall within the tank and supported in a spaced relation to the walls and cover thereof, a belt operable in the longitudinal grooves, one of the ends being concave and 20 the edges forming flanges having open-ended slots, a shaft adapted to rotate in the slots, a roller on said shaft and provided centrally with a sprocket to engage with the belt, said roller operating in the concave end 25 of the wall, a film carrier comprising a U-shaped arm carrying clips at its outer ends,

a support member secured thereto and having at its lower end a roller for operating on the lower wall of the tank, a plurality of arms angularly extending from the support and having their other ends connected to and in a spaced relation with said chain, means for guiding and spacing the films when in the extended condition, and means for moving said belt and film carrier. 30

6. A photographic developing machine, comprising a tank having a cover, a film spool holder carried by the bottom wall of the tank for holding spools within said tank, and means for drawing a film vertically end- 40 wise in a horizontal plane through the tank, said means including a movable film carrier, operable on the bottom wall of the tank for supporting and spacing the film above said bottom wall. 45

In testimony whereof I affix my signature in presence of two witnesses.
